UNITED STATES PATENT OFFICE.

EMIL RUDOLPH RÖSSLER, OF SMESTAD, NEAR OSLO, NORWAY.

ADVERTISING DEVICE.

Application September 30, 1926; Serial No. 138,694; and in Norway October 9, 1925.

The present invention relates to a lamp or frame arrangement which is adapted to be used in connection with a suitable sign board for advertising purposes. It is the object of my invention to provide means whereby such frame may be easily altered and rearranged to change the form or design thereof, so that a great number of frame types may be produced by means of few different elements of which the frames are composed.

The annexed drawings illustrate my invention by way of example.

Fig. 1 shows two pivotally connected links according to my invention, as seen from the front side thereof.

Fig. 2 is a top view thereof.

Fig. 3 is a rear view thereof and

Fig. 4 is a section of a link showing a method of securing an advertising plate therein.

Figs. 5-8 show different forms of a composite lamp or frame arrangement according to my invention.

Referring to Figs. 1-4 the links proper 1 are pivotally connected to an intermediate link 3 by means of bolts 2. On the bolt 2 are screwed wing nuts 4 by means of which the links may be secured in the desired relative positions. The links 1 have the shape of hollow channel formed bodies of any desired cross section, and the inner front edge of each link is provided with a flange 5 preferably lined with some suitable tightening material such as felt. Against the said flanges 5 may rest a glass plate or advertising plate 7 (Fig. 4) as described more fully below, suitable pressing means, such as tiltable arms 6 being arranged to back the edge of the plate 7. Within some or each of the links is situated a lamp 8 the light of which passes through the open rear side of the link and enlightens the plate 7.

By the use of a number of links of the described types, frames or advertising lamps of different shapes may easily be produced, and some types of such frames are diagrammatically shown in Figs. 5-8. Within such frames are placed a transparent plate 7 provided with the advertising signs or figures proper, which is enlightened from the rear side by the lamps 8 situated in the links 1, so that the arrangement is as well adapted for use in the evening and night as in the day.

In order that no light from the lamps 8

shall penetrate at the places where the links 1 are connected by means of the middle links 3, flexible plates or shields 9 are arranged, adapted to always cover the opening between the links 1. It will be understood that the number of links 1 and intermediate links 3 may be varied as desired, and the relative positions of such links may also be varied as desired, whereby practically any desired shape of the frame may be obtained.

The links may also be given different lengths in order to further vary the possible frame shapes. In Fig. 7 are illustrated some shorter links designated by the numeral 10.

In order to further secure the several links in the desired relative positions, means additional to the said wing nuts 4 may be used.

Thus Fig. 3 illustrates how an arm 11 may be pivotally secured to one of the bolts 2 and adapted to be swung on to the bolt 2 on the adjacent link, engaging said bolt by means of a notch 12 and adapted to be secured by means of the wing nut at that link.

13 (Figs. 5-8) is an arm which may be provided at suitable points of the frame, being detachably secured to some intermediate link. At its outer free end such arm may carry an electric lamp or torch 14 or some other decorative means.

An advertising arrangement of the described type may be used as an enlightened sign board in the night, displaying silhouettes or other advertising figures pointed on the plate 7. In day light the arrangement will appear as an ordinary sign board 7 surrounded by a frame built up from the several links.

Obviously the shape and the dimensions of the links as well as details in the construction thereof may be varied within the scope of the invention.

Having now particularly described and ascertained the nature of my said invention and in what manner the same is to be performed, I declare that what I claim is:

1. A frame for sign boards consisting of pivotally connected links and means for adjustably securing the links in any desired relative position.

2. A frame for sign boards consisting of pivotally connected links, means for supporting a sign board in said links, and means for adjustably securing the links in any desired relative position.

3. A frame for sign boards consisting of

pivotaly connected links, a flange on each link for supporting a sign board in said links, and means for adjustably securing the links in any desired relative position.

6. A frame for sign boards consisting of pivotaly connected links, a flange on each link for supporting a sign board in said links, clamping means for securing the sign board to the flanges, and means for adjustably securing the links in any desired relative position.

7. A frame for sign boards consisting of pivotaly connected hollow links, the links having openings directed toward the inner side of the composite frame, illuminating means in the links, means for preventing the light from the illuminating means from penetrating through the pivotal connections of the links, and means for adjustably securing the links in any desired position.

8. A frame for sign boards consisting of pivotaly connected hollow links, the links having openings directed toward the inner side of the composite frame, illuminating means in the links, and means for adjustably securing the links in any desired position.

means in the links, and means for adjustably securing the links in any desired position.

9. A frame for sign boards consisting of pivotaly connected hollow links, the links having openings directed toward the inner side of the composite frame, illuminating means in the links, means for preventing the light from the illuminating means from penetrating through the pivotal connections of the links, and means for adjustably securing the links in any desired position.

In testimony whereof I affix my signature.

EMIL RUDOLPH RÖSSLER.
